UNITED STATES PATENT OFFICE.

REUBEN BOYD MILLER, OF THE UNITED STATES ARMY.

AIR MOISTENING AND COOLING ATTACHMENT FOR RADIATORS.

1,116,097.

Specification of Letters Patent.

Patented Nov. 3, 1914.

Application filed June 19, 1911. Serial No. 634,061.

To all whom it may concern:

Be it known that I, REUBEN B. MILLER, captain, Medical Corps, United States Army, a citizen of the United States, at 5 present stationed at Army and Navy Hospital, Hot Springs, Arkansas, have invented certain new and useful Improvements in Air Moistening and Cooling Attachments for Radiators; and I do hereby declare the following to be a full, clear, and exact description of the invention, such as will enable others skilled in the art to which it appertains to make and use the same.

This invention relates to improvements in 15 air moisteners, and is especially designed for attachment to a radiator or stove for supplying the heated air in a room with aqueous vapor.

The object of the invention is to provide 20 a simple device of the above character, which will maintain sufficient moisture in the heated atmosphere of the room to prevent injurious effects of dry air on the inhabitants or the desiccating and cracking of 25 the wood work and furniture.

With the above and other objects in view, the invention consists in certain combinations and arrangements of the parts hereinafter described, and the novel features thereof 30 will be particularly pointed out in the appended claim.

The preferred embodiment of my invention is illustrated in the accompanying drawings in which like characters of reference indicate corresponding parts.

Figure 1 is a cross section of a radiator with my invention attached thereto; Fig. 2 is a perspective view of an air moistener constructed in accordance with the invention; 40 and Fig. 3 is a sectional view illustrating the manner of securing the fabric to the frame.

In the drawings 1 represents a radiator in section having the usual spacing lugs 2, 45 which lugs are used for attachment of hooks 3 for carrying the air moistener.

The air moistener consists of a long narrow receptacle 4 for holding water, preferably formed of sheet material with a wire 50 5 rolled in its rim 6. The top portion of the receptacle 4, at its rear side, is recessed as at 7 and the hooks 3 are slidingly connected by means of eyes 8 to the portions

of the wire 5 spanning the recesses. Projecting upwardly from the inside of the receptacle 4 and rigidly secured to its rear corners are legs 9 of a rectangular frame 55 preferably formed of a round bar, and over the top of said frame is hung one or more thicknesses of porous moisture absorbing 60 fabric 10 which depends into the water contained in the receptacle and will freely permit the air to blow therethrough.

In order to secure the fabric to the top of the frame and also permit of its ready removal for replacing same by new fabric, I provide a spring clip of flat material having a rounding head 11, the free edges of which are bent outwardly as at 12, to form guides for the spring clip, when pressing 70 same over the fabric 10 hung over the top of the frame.

Although the air moistener is shown attached to a radiator, it is obvious that my improved device may be set in an open window during warm weather, and as the air blows through the porous absorbing material it will take up moisture and to a certain extent be cooled.

It is apparent from the above that the 80 moistened fabric will keep the atmosphere of a room in a healthy and suitable condition, and the fabric may be readily removed from the frame for the purpose of washing same or replacing it by new fabric. 85

Although the elements set forth and described are well adapted to accomplish the intended purposes, it is to be understood that various changes in the form, proportion and minor details of construction may be resorted to without sacrificing any of the advantages or departing from the spirit of the invention.

Having fully described my invention, what I claim is:—

An air moistener for radiators, comprising an open top water receptacle, a pair of hooks adjustably spaced on said receptacle for engaging the radiator to support said receptacle in contact therewith, a rod bent 100 at right angles near its ends, the said ends projecting into said receptacle, porous absorbent material hung across the central portion of said rod, and having its ends dipping into the open top of said receptacle 105 adjacent to the radiator walls and in the

path of the heated air currents flowing from the radiator, and a resilient plate substantially in the form of an inverted U-shaped trough adapted to spring over said rod and 5 to secure the absorbent material thereto, and also to form a guard for the upper portion thereof, substantially as described.

In testimony whereof, I affix my signature, in presence of two witnesses.

REUBEN BOYD MILLER.

Witnesses:

JOHN T. SIMMONS,
ERNEST E. MALLORY.
